LUGGAGE LOCK

Lothar R. Zifferer, York, Pa., assignor to New Standard Corporation, Mount Joy, Pa., a corporation of Pennsylvania

Application October 22, 1949, Serial No. 5,660

Term of patent 14 years

(Cl. D50—7)

To all whom it may concern:

Be it known that I, Lothar R. Zifferer, a citizen of the United States, residing at York, county of York, and State of Pennsylvania, have invented a new, original, and ornamental Design for a Luggage Lock, of which the following is a specification, reference being had to the accompanying drawing, forming part thereof.

Figure 1 is a view in perspective of a luggage lock, showing my new design;

Fig. 2 is a plan view thereof; and

Fig. 3 is an end elevation thereof.

I claim:

The ornamental design for a luggage lock, as shown.

LOTHAR R. ZIFFERER.
